UNITED STATES PATENT OFFICE

149,113

DESIGN FOR A PISTOL

John F. Dille, Evanston, Ill.

Application October 17, 1946, Serial No. 134,009

Term of patent 7 years

(Cl. D34—15)

To all whom it may concern:

Be it known that I, John F. Dille, a citizen of the United States, residing in Evanston, in the county of Cook and State of Illinois, have invented a new, original, and ornamental Design for a Pistol, of which the following is a specification, reference being had to the accompanying drawing, forming a part thereof, in which:

Fig. 1 is a side view of a pistol showing my new design;

Fig. 2 is a top view;

Fig. 3 is a front view; and

Fig. 4 is a rear view.

I claim:

The ornamental design for a pistol, as shown.

JOHN F. DILLE.
